SHAVING LATHER HEATER AND DISPENSER

Samuel L. McNair, Overland Park, Kans., assignor to
Dazey Products Co., Kansas City, Mo.

Filed Aug. 5, 1974, Ser. No. 494,487

Term of patent 14 years

Int. Cl. D9—01

U.S. Cl. D6—95

Fig. 1.

Fig. 3.

Fig. 2.

Fig. 4.

Fig. 5.

Fig. 6.

FIG. 1 is a side perspective view of a shaving lather heater and dispenser showing my new design;

FIG. 2 is a top plan view of same;

FIG. 3 is a rear elevational view of same;

FIG. 4 is a front elevational view of same;

FIG. 5 is a side elevational view of same; the other side being substantially the same in appearance; and

FIG. 6 is a bottom plan view of same.

I claim:

The ornamental design for a shaving lather heater and dispenser, as shown and described.
